US00D934292S

(12) **United States Design Patent** (10) **Patent No.:** **US D934,292 S**
Dedonato et al. (45) **Date of Patent:** **** Oct. 26, 2021**

(54) **DISPLAY PANEL OR PORTION THEREOF WITH GRAPHICAL USER INTERFACE**

(71) Applicant: **MAGIC LEAP, INC.**, Plantation, FL (US)

(72) Inventors: **Amy Dedonato**, Plantation, FL (US); **Lorena Pazmino**, Wilton Manors, FL (US); **Yan Xu**, San Jose, CA (US); **Marc Coleman Shelton**, Fort Lauderdale, FL (US); **James M. Powderly**, Fort Lauderdale, FL (US); **Dylan Nathan**, Los Angeles, CA (US); **Li Chin Lin**, Seattle, WA (US)

(73) Assignee: **Magic Leap, Inc.**, Plantation, FL (US)

(**) Term: **15 Years**

(21) Appl. No.: **29/709,029**

(22) Filed: **Oct. 10, 2019**

Related U.S. Application Data

(63) Continuation of application No. 29/640,710, filed on Mar. 16, 2018, now Pat. No. Des. 868,108.

(57) **CLAIM**

The ornamental design for a display panel or portion thereof with graphical user interface, as shown and described.

DESCRIPTION

The FIGURE is a front view of a display panel or portion thereof with graphical user interface showing our design. The outermost broken line rectangle illustrates a display panel or portion thereof that forms no part of the claimed design. The remaining broken lines, including all text, illustrate portions of the graphical user interface or a mixed reality environment, and form no part of the claimed design.
